2,133,766

PURIFICATION OF NAPHTHENIC ACIDS

Frederick J. Ewing, Pasadena, Calif., assignor to
 Union Oil Company of California, Los Angeles,
 Calif., a corporation of California

No Drawing. Original application March 12,
 1934, Serial No. 715,181. Divided and this ap-
 plication February 28, 1936, Serial No. 66,221

11 Claims. (Cl. 260—514)

This invention relates to naphthenic acids and more particularly refers to a process for their deodorization and decoloration, and is a division of my copending application Serial No. 5 715,181, filed March 12, 1934.

It is an object of my invention to present a simple, efficient and thoroughly satisfactory process for obtaining naphthenic acids of a light color and bland odor.

10 Naphthenic acids, such as may be obtained by acidifying various alkaline liquors arising during the refining of petroleum or shale oil fractions, constitute a complex mixture of acidic compounds containing principally carbon, hydrogen and oxygen. They range from comparatively low boiling liquids to materials which are solid or semi-solid at ordinary temperatures. Their viscosities as well as their boiling points are generally closely correlated to the viscosities and boiling points of the hydrocarbon fractions in which they are present.

15 The crude naphthenic acids which are obtained by acidifying the alkaline liquors referred to above, contain varying amounts of phenols and carbonaceous materials and they possess a very dark to black color and a disagreeable odor. When these crude acids are freed from phenolic materials by careful acidification, neutralization and distillation as hereinafter described to produce what will hereinafter be called "semi-refined" acids, the amount of carbonaceous materials appears to increase as a result of which 3% to 5% thereof and sometimes even greater amounts have been encountered in the dephenolized naphthenic acids. The major portion of this carbonaceous material is present in a finely suspended or colloidal state and is in most instances not removable by settling or centrifuging. The presence of this material is partially responsible for the dark and turbid color of the naphthenic acids and renders their sale as a commercial product practically impossible. It is, therefore, desirable to obtain naphthenic acids which are substantially free from these undesirable materials.

20 It has been customary to distill the naphthenic acids to remove this carbonaceous material. However, this distillation is not applicable in all instances in that it is usually accompanied by plugging of the still due to the presence of the aforementioned carbonaceous material. Moreover, the equipment used for this distillation is subject to a rapid deterioration due to the corrosive action of the naphthenic acids on iron or on other metals normally used in the construc-

tion of stills. The naphthenic acids which are recovered as an overhead product of such a distillation are of a substantially improved color, but this color on standing rapidly darkens and in some instances becomes nearly as dark as before distillation. 5

A more efficient and satisfactory method for removing this carbonaceous material consists in treating the crude or semi-refined naphthenic acids with any of the common oxygen-containing inorganic acids, such as sulphuric acid of suitable concentration, whereby a coagulation and separation of this carbonaceous material is brought about. The product obtained by this method of treatment which will be described in greater detail later on, is of a somewhat improved color but still is inapplicable without further treatment in any instances where a light colored product is desired. 10 15

I have discovered that naphthenic acids from which the carbonaceous materials have been removed by either of the two above identified processes or by any other physical or chemical means such as those hereinafter set forth, may be worked up into a product of excellent light color 20 which does not change or darken on exposure, and bland odor, by treating them subsequently to the removal of the carbonaceous materials with an adsorbent material, such as clay, fuller's earth, "Filtrol" or activated carbon. By so operating, a distillation of the naphthenic acids to bring about a further improvement in color and odor may be eliminated. This treatment with adsorbent materials is substantially ineffective 25 where the carbonaceous materials have not been previously removed. However, the acid treatment of the naphthenic acids for purposes of removing the carbonaceous materials renders them especially suitable for further purification 30 35 by means of the adsorbent. 40

While it is customary to remove the residual inorganic acidity from the naphthenic acids which have been treated with an oxygen-containing inorganic acid such as sulphuric acid for the removal of the admixed carbonaceous materials, 45 experiments have indicated that the treatment with the adsorbent material may be substantially improved by eliminating the water wash for the removal of this inorganic acidity, and contacting the naphthenic acids with the adsorbent material in the presence of small amounts of an inorganic acid thus remaining in the naphthenic acids. As a slight modification of the above method of treatment, I may activate the clay or other adsorbent with small amounts of sulphuric 50 55

acid or any of the other acids set forth herein by adding these acids to the adsorbent and treating the naphthenic acids with the mixture of adsorbent and acid. Activation of the clay with acid salts, i. e. a salt which on solution liberates hydrogen ion, produces substantially identical results as in the case where an inorganic acid is used for activating the adsorbent. If desired, I may also add my inorganic acid directly to the naphthenic acids before adding the adsorbent material, whereby the same effect of activation of the adsorbent is obtained.

Therefore, my invention broadly resides in a process for obtaining naphthenic acids of a stable light color and bland odor which comprises removing the carbonaceous material present in these acids and subsequently treating the product so obtained by means of an adsorbing agent.

My invention likewise extends to a process for purifying and decolorizing naphthenic acids wherein the adsorbing agent used has been activated or treated with an inorganic acid such as sulphuric acid or with an acid salt such as sodium acid sulphate or sodium acid phosphate or the like.

The term "alkaline liquor" referred to earlier in this specification relates not only to the alkaline solution containing naphthenic acids and other materials taken up by the alkali on treating a petroleum fraction but also relates to the alkaline solution obtained by treating the extract phase which is formed on treating a petroleum fraction with a selective solvent such as liquid sulphur dioxide, dichlorethyl ether, nitrobenzene, furfural, isopropyl alcohol, dimethyl sulphate, etc., with caustic soda, caustic potash or any other alkaline reagent.

When an alkaline liquor, arising on treatment of petroleum fractions such as any of those described above, is acidified with any of the well known inorganic acids a distinct phase separates out which phase is then adjusted by means of sodium carbonate or sodium hydroxide (or their equivalents) to a pH of about 9. By so operating there is formed a mixture consisting of sodium naphthenates, phenols and admixed hydrocarbons which is then subjected to distillation which removes the phenols and hydrocarbons overhead. The still bottoms then consist of sodium naphthenates, which, when dissolved in water form a solution from which the semi-refined acids are obtained by the addition of a mineral acid such as sulphuric acid.

These semi-refined naphthenic acids contain from 3% to 5% of carbonaceous material, only a small fraction of which is removable by settling or centrifuging. Apparently this material is present in some kind of colloidal suspension which renders its separation extremely difficult. In addition, they are of a red to dark black color rendering their use as a commercial product practically impossible.

In a copending application, Serial No. 696,914, there is set forth a process for removing carbonaceous materials from crude or semi-refined naphthenic acids which process, in its simplest aspect, relates to the treatment of naphthenic acids with oxygen-containing inorganic acids of such concentration that the formation of emulsions is substantially prevented and a ready separation of the sludge formed upon acid treatment may be realized. For instance, sulphuric acid, having a concentration between approximately 50% and 83% has been found especially suitable.

While any oxygen-containing inorganic acid such

as iodic acid, chloric acid or bromic acid has been disclosed as suitable for the separation of the carbonaceous materials, I preferably use an oxygen-containing inorganic acid chosen from the class comprising sulphuric, phosphoric 5 and nitric acid. The amounts of these acids to be used are relatively small and range from $\frac{1}{2}$ to 10 volume percent of the naphthenic acids.

If desired, the acid treatment referred to above, may be carried out in the presence of a hydrocarbon diluent such as liquid propane, butane, cleaner's naphtha (a petroleum fraction boiling between 200-300° F.) benzol or the like. The addition of any of the above mentioned diluents greatly facilitates the separation of the sludge 15 formed as a result of the acid treatment.

I have discovered in connection with the present invention that a similar facilitation of the sludge settling may be brought about by increasing the temperature of the acid treat to 20 temperatures ranging from approximately 100 to 200° F.

While in the above identified application it is indicated that the strength of the acid used for the removal of the carbonaceous materials 25 should preferably be between 50% and 83%, I have found that acids of greater concentration may be used as well and that such acids are especially effective when a naphthenic acid product of light color is desired. As such concentrated acids are more or less miscible with the naphthenic acids, steps must be taken to provide for the removal of these acids as well as for the acid sludge. Thus 95% sulphuric acid, fuming sulphuric acid (containing about 15% dissolved SO₃) as well as sulphuric acid having a concentration of between 83% and 95%, tend to be substantially miscible with the naphthenic acids.

When the impure naphthenic acids containing 40 carbonaceous materials are contacted with $\frac{1}{2}$ to 10 volume percent of sulphuric acid having a concentration substantially that set out above, no separation into phases takes place, although in some cases the carbonaceous materials agglomerate. However, when portions of more dilute sulphuric acid (e. g. sulphuric acid of 60% concentration) are added to the mixture of impure naphthenic acids and the highly concentrated sulphuric acid, a separation into a naphthenic acid phase and a phase consisting of sludge, sulphuric acid and carbonaceous materials readily takes place as soon as the total acid concentration has been reduced to approximately 83%. The carbonaceous materials are found in the 55 sludge and sulphuric acid layer.

Another method of obtaining phase separation when such concentrated acids are being used to obtain a higher degree of decolorization and deodorization consists in diluting the naphthenic acids either before or after treatment with the concentrated sulphuric acid, with a material capable of reducing the solvent power of the sulphuric acid for the naphthenic acid. Liquid propane, cleaners' naphtha, petroleum ether or other light paraffinic solvents may be used for this purpose. Aromatic hydrocarbons such as benzol, toluol or their homologues may be used for the purpose indicated above but are not as desirable as the paraffinic solvents on account of their solubility in the concentrated sulphuric acid. The above mentioned diluents may be removed from the naphthenic acids by distillation or by extracting the mixture of naphthenic acids and diluent with an alkaline material, such as caustic 70 75

soda and liberating the naphthenic acids from their salts so produced by means of an inorganic acid, such as H_2SO_4 , HCl or the like.

The so treated acids are then treated with the adsorbent material in the manner described herein, to further improve their color and odor.

When the crude or semi-refined naphthenic acids, before subjecting them to the above mentioned acid treatment are contacted with an adsorbent material while agitating the mixture either by air or by mechanical means, no improvement in color or odor of the naphthenic acids is brought about after filtering off the latter from the adsorbent. Even in the case where the naphthenic acids and adsorbent were heated to temperatures substantially in excess of atmospheric, no improvement in the color thereof could be noted.

When, however, the carbonaceous materials are removed from the naphthenic acids by means of any of the oxygen-containing inorganic acids set forth in the above identified copending application or by any other means and the so treated acids are subjected to a treatment with an adsorbent material a vast improvement in the color and odor of the final product as compared with the crude or semi-refined acids is brought about.

For example, in a preliminary experiment, impure naphthenic acids which had been treated with 0.5% by volume of 80% sulphuric acid for purposes of removing the carbonaceous materials admixed therewith, and which had a color in excess of 8 N. P. A., were contacted with 10% of fuller's earth for 5 minutes at a temperature of 300° F. After filtering off the adsorbent and the materials taken up thereby, naphthenic acids having a color of from 4 $\frac{3}{4}$ to 5 $\frac{1}{4}$ N. P. A. was obtained. The same acids, without preliminary acid treatment, when contacted with the same adsorbent under identical conditions showed no improvement in color whatsoever.

Considering my process in greater detail, a charge of crude or semi-refined naphthenic acids contaminated with carbonaceous materials and having a dark red to black color, is treated with an oxygen-containing inorganic acid such as sulphuric acid. The amount of acid used may vary between $\frac{1}{2}$ to 10 volume percent of the naphthenic acids. The concentration thereof is chosen preferably between 50% and 83%. The mixture of inorganic acid and naphthenic acids is agitated with air or by mechanical means preferably for a period of from 15 to 30 minutes. Just before the agitation is stopped, a small amount of clay or water is added to facilitate the separation of the acid sludge. The sludge is subsequently separated together with the carbonaceous materials. The naphthenic acids are then washed with water to remove any inorganic acidity and are then blown at a slightly elevated temperature with natural gas or any inert hydrocarbon gas to remove the remaining traces of water.

The naphthenic acids, treated as indicated above, have a much improved color but are still too dark for a commercial product. These acids are now mixed at ordinary temperatures or at least at temperatures below the boiling point of water, with the adsorbent, the amount of the latter being somewhere between approximately 8 and 20%, depending upon the particular charge of the naphthenic acids and the degree of decolorization desired. The mixture of naphthenic acids and adsorbent is heated while agitating with air or by other means, such as a mechanical stirrer up to a temperature ranging from ap-

proximately 225° F. to 300° F. or higher. As soon as the desired temperature has been reached, which in most instances is somewhere between 250° F. and 325° F., the heating is discontinued or slowed down and the mixture is maintained at this temperature for a period of approximately 2 to 5 minutes. The agitation is then discontinued, and the purified and decolorized naphthenic acids are separated from the adsorbent by filtering them while still in a heated condition through a suitable filtering device such as a Sweetland filter. It is not essential that the filtering process takes place at an elevated temperature. However, the viscosity of the naphthenic acids at an elevated temperature is such to allow a more rapid filtration. The naphthenic acids so obtained have a color of from 4 to 6 N. P. A. as compared with a color in excess of 8 N. P. A. before treatment with the adsorbent.

As a slight modification of the above operation, it may be desirable in connection with the purification of the naphthenic acids to eliminate the water wash of the naphthenic acids for removal of the inorganic acidity and thus leave a small amount of sulphuric acid or any equivalent acid, admixed with the naphthenic acids. When the naphthenic acids containing a small amount of inorganic acidity are treated with the adsorbent material a product is obtained which has a lighter color than one which had been water washed before treatment with the adsorbent. It is believed that the presence of the inorganic acid tends to activate the adsorbent material.

If for any reason a water wash of the naphthenic acids should be deemed desirable, the adsorbent may be activated by addition of small amounts of an inorganic acid such as that used for the removal of the carbonaceous materials or these acids may be directly added to the naphthenic acids before treatment with the adsorbent as pointed out above. Acid salts such as sodium acid sulphate, sodium acid phosphate or the like may be substituted for the inorganic acids and produce almost identical results. It has been found advantageous, especially in the case where the residual inorganic acid is used for activating the adsorbent material, to introduce a small amount of water with the adsorbent, or adding the adsorbent in the form of a water containing slurry. The presence of the water appears to cause a better dispersion of the inorganic acid and hence a better activation of the adsorbent material.

The amount of the adsorbent to be used will vary with the naphthenic acid stock to be treated, the degree of decolorization and the particular adsorbent used. In general, amounts of from 8 to 20% of the adsorbent material as indicated above are sufficient, although in certain instances where a light colored product is desired, from 40% to 51% of the adsorbent material may be required.

The treating temperature with the adsorbent material referred to above has been indicated to be somewhere between approximately 225° F. to 325° F. However, very successful treatments have been made at temperatures of 400° F. or above. The above temperature range is merely my preferred operating temperature. Naphthenic acids, freed from carbonaceous materials by any of the processes set forth herein, show an improvement in color even when treated at room temperature. The upper treating temperature limit is largely controlled by the boiling point and flash point of the naphthenic acids.

The time interval during which the naphthenic acids are contacted with the adsorbent material

may vary over a wide range. In general, 2 to 15 minutes are sufficient to bring about the desired decolorization although contact times considerably in excess of these may be necessary in certain instances.

The following specific examples are illustrative of my invention:

Example 1

10 Fifteen hundred (1500) cubic centimeters of semi-refined naphthenic acids containing from 3% to 5% of carbonaceous materials were agitated with 75 cubic centimeters of 80% sulphuric acid for one-half hour. Immediately before the 15 agitation was stopped, 5 grams of diatomaceous earth were added to the mixture to facilitate the

The finished product in each instance had an acid number of from 289-290 as compared with an acid number of 284 before treatment.

The following example is illustrative of the improved decolorizing action of the adsorbent when small amounts of sulphuric acid are left in the naphthenic acids which in this case is accomplished by eliminating the water wash. The stock used consisted of semi-refined naphthenic acids which had been agitated with 5 volume percent of 80% H_2SO_4 . (About 1% of clay was added to facilitate the settling of the sludge.) The results of the treatment of these acids with the adsorbent in comparison with naphthenic acids which had been water washed for removal of the sludge are given below:

Table II

20	Type of acids	Semi-refined naphthenic acid treated as indicated above	Same	Same	Same	20
25	Water wash..... Clay used..... Clay treating temperature..... Duration of clay treating..... Color of filtrate.....	None..... 10% "Filtrol"..... 200° F..... 2 min..... 4 1/4 N. P. A..... Same..... 10% "Filtrol"..... 225° F..... 2 min..... 6 1/2 N. P. A.....	25

30 settling of the sludge. The naphthenic acids, now substantially free from the above mentioned carbonaceous materials, were washed with hot salt water and after removal of the wash water, were blown bright with natural gas, at a temperature of about 180° F. They were transparent when 35 viewed through the neck of a four ounce oil sample bottle, whereas the untreated acids were black and had no such transparency.

35 The naphthenic acids which had been purified as indicated above were then mixed at room temperature with approximately 10% by weight of Filtrol. Individual samples of the mixture were 40 slowly heated up to a temperature of approximately 212° F. to cause a dehydration of the adsorbent in such a manner that no undue foaming of the mass occurred and they were then heated to various temperatures ranging from 45 225° F. to 300° F. The naphthenic acid charges, during heating, were agitated by means of a slow current of air. When the desired temperature 50 had been reached, the heating of the charges was slowed down or discontinued and the mixture of naphthenic acid and clay was allowed to remain at this temperature for approximately two minutes. The acids were then removed from the 55 adsorbent materials by passing the mixture through a suitable filtering device. This filtration was carried out at substantially the same elevated temperature which prevailed during the clay treatment which greatly facilitated the rate 60 of filtration.

65 The finished product had a permanent color of from 4 1/4 to 5 1/4 N. P. A. and was of a bland to sweet odor as may be seen from the following table:

In case an extremely light colored product such as one having a color of between 2 1/2 and 3 1/2 N. P. A. is desired, the treatment with the adsorbent material, or with an adsorbent material which has been activated by means of sulphuric acid, phosphoric acid or the like, or by means of an acid salt as indicated above, may be repeated. Thus, a product having a color of 3 1/2 N. P. A. was obtained by treating naphthenic acids which had been purified as indicated above and which had a color of 4 1/4 N. P. A. with 10% of "Filtrol" which had been activated by means of 0.33% of 60% sulphuric acid, at a temperature of 325° F. A small amount of water (10% by volume of the naphthenic acids) was added to the adsorbent before introduction into the naphthenic acids. The time of contact with the adsorbent material was approximately 15 minutes.

While the removal of the carbonaceous material from the naphthenic acids has been disclosed to be performed by means of distillation, or preferably by treatment with an oxygen-containing inorganic acid, such as sulphuric acid or the like, other means may be employed for the same purpose. Thus, carbonaceous materials may be readily removed from naphthenic acids which are present by means of sulphur trioxide dissolved in cleaners' naphtha or kerosene, or by means of concentrated aqueous solution of ferric chloride or zinc chloride in amounts substantially the same as used in the case of the inorganic acids described above, or by passing dry hydrogen chloride or other hydrogen halides into the naphthenic acids containing the carbonaceous materials, or by treating the impure naph-

thenic acids with concentrated aqueous solutions of hydrogen halides. The function of any of the above reagents is to coagulate the carbonaceous materials to particles large enough to settle under the influence of gravity. I have discovered that naphthenic acids which have been freed from carbonaceous material by means of any of the above mentioned reagents are readily amenable to treatment with an adsorbent material in the 10 manner described above.

While the process of deodorization and decolorization has been particularly described in connection with phenol-free or "semi-refined" naphthenic acids, it may equally well be applied 15 to naphthenic acids which have not been subjected to a process for the removal of phenolic materials such as that previously described. However, such products do not possess as desirable a color and odor as the naphthenic acids 20 which had been freed from phenolic material.

The term "blowing bright" referred to earlier in this specification, relates to the treatment of naphthenic acids or other hydrocarbon products with an inert gas, such as air or methane, ethane, 25 and the like, for removing traces of water which remain in the naphthenic acids or other liquid hydrocarbon after a treatment thereof with water or aqueous solutions.

The term "Filtrol" signifies an acid treated 30 clay or fuller's earth. The product commercially marketed under that name consists of fuller's earth which has been activated by means of dilute sulphuric acid.

The term "N. P. A. color" used in this specification relates to a color grade of a liquid obtained by means of the Union Petroleum Colorimeter adapted as a standard of the National Petroleum Association in 1915. A detailed description of the apparatus, method of test and 40 significance of scale readings may be found in "David T. Day's Handbook of Petroleum Ind., 1922, vol. 1, page 656". For example N. P. A. 0.5—1 indicates a light, almost water-white color, wherein N. P. A. 3 indicates a yellow to straw 45 color and N. P. A. 7 to 8 indicates a product of a dark reddish to brown color.

The process herein set forth is applicable to all varieties of naphthenic acids. It may be 50 equally well applied to naphthenic acids derived from a light petroleum fraction such as kerosene as to acids derived from the higher boiling fractions such as gas oil or lubricating oil.

The examples set forth herein are merely illustrative of the generic invention and many variations thereof will be obvious to those skilled in the art.

I claim:

1. A method of purifying naphthenic acids

which comprises treating said acids at an elevated temperature ranging from approximately 100° to 200° F. with sulfuric acid of a strength capable of agglomerating carbonaceous impurities.

2. A method as claimed in claim 1 in which the treatment is carried out in the presence of a water immiscible diluent.

3. A method of treating naphthenic acids which comprises diluting said acids with a water 10 immiscible solvent which has a boiling point range different from that of the naphthenic acid, treating the diluted naphthenic acid with .5 to 10% by volume of concentrated sulphuric acid, and then recovering the treated naphthenic acids 15 dissolved in the water immiscible solvent.

4. A method as claimed in claim 3 in which the sulphuric acid is about 95.0% in strength.

5. A method as claimed in claim 3 in which the solvent is petroleum naphtha.

6. The process of purifying crude naphthenic acids which comprises diluting the acids with a water-immiscible solvent which has a distillation boiling point range different from that of the crude acid, treating the diluted crude acids 25 with a strong sulfuric acid and recovering the treated naphthenic acids dissolved in the water-immiscible solvent.

7. The process of purifying crude naphthenic acids which comprises diluting the acids with a 30 water-immiscible solvent of lower distillation boiling point range than that of the crude acids, treating the diluted acids with a strong sulfuric acid and recovering the treated naphthenic acids dissolved in the water-immiscible solvent.

8. A method as claimed in claim 6 in which the water-immiscible solvent is a hydrocarbon.

9. A method as claimed in claim 6 in which the water-immiscible solvent is a petroleum naphtha.

10. A method of treating naphthenic acids which comprises diluting said acids with a water-immiscible solvent which has a boiling point range different from that of the naphthenic acids, and treating the diluted naphthenic acids 45 with .5 to 10% by volume of concentrated sulphuric acid.

11. A process for purifying naphthenic acids containing admixed carbonaceous materials and color bodies, the steps of diluting the said 50 naphthenic acids with a low boiling hydrocarbon fraction, contacting the diluted acids with sulfuric acid having a strength of between 50 and 83%, separating the agglomerated materials and acid sludge, and separating the hydrocarbon diluent from the naphthenic acids.

FREDERICK J. EWING.
